WORK SUPPORTING MECHANISM

Joseph Thomas Fagan, Rochester, N. Y., assignor
to United Shoe Machinery Corporation, Paterson, N. J., a corporation of New Jersey

Application June 5, 1935, Serial No. 25,103

8 Claims. (Cl. 1—19)

This invention relates to work supporting and positioning mechanism and is illustrated herein as embodied in a fastening inserting machine particularly adapted to secure sole members to shoes.

5 In the manufacture of several types of boots and shoes it is customary to secure outsoles temporarily to shoes by the use of fastenings extending through the outsole and insole and into the body of the last to prevent displacement of the sole during subsequent operations. For example, in the manufacture of welt shoes an outsole is temporarily secured to the shoe by an adhesive, such as rubber cement and, to prevent creeping of the outsole while the shoe is clamped to cause the outsole to conform to the bottom of the shoe, the heel end of the outsole is fastened to the shoe by tack or other fastening which extends through the insole and into the last through a hole formed in a metal plate secured to the heel end of the last. Unless the shoe is properly located by the operator with the hole in the metal heel plate of the last directly below the nozzle of the fastening inserting machine, the tack or other fastening will strike the metal heel plate and will be crippled so that another fastening must be driven.

10 The operator holds the shoe in his hand and positions it in accordance with his personal judgment, the hole in the heel plate being out of sight. The proper positioning of the shoe relatively to the nozzle, therefore, requires skill and consumes time with consequent loss of production of the machine.

15 It is also important that the heel end of the outsole be brought into close contact with the heel end of the shoe and to accomplish this the operator must exert considerable pressure against the nozzle of the machine. This exertion of pressure during each fastening inserting operation tires the operator, with the result that toward the end 20 of a day's work the operator does not exert sufficient pressure against the shoe to bring the heel end of the outsole into close engagement with the shoe.

An object of the present invention is to provide 25 a mechanism by the use of which the above-mentioned difficulties will be overcome. To this end one feature of the invention resides in a fastening inserting machine provided with a single means constructed and arranged to engage a work piece 30 to position the work relatively to a fastening inserting means and to support the work during the fastening inserting operation. As illustrated a bracket is secured to the machine frame and rotating roll of rubber or other resilient and somewhat yielding material is mounted in the forward

35 end of the bracket, the roll being provided with a groove the walls of which engage the heel end of a lasted shoe to locate the heel end of the shoe longitudinally relatively to the nozzle and to force the shoe against the nozzle. The bracket is arranged 40 to be located in adjusted position to position the groove of the roll behind the nozzle a distance sufficient to insure that a fastening will be driven substantially into the central portion of the heel end of a shoe engaged by the roll.

45 With the above and other objects and features in view, the invention will be described with reference to the accompanying drawing and pointed out in the appended claims.

In the drawing,

50 Fig. 1 is a view in side elevation partly in section of the lower portion of the head of a machine embodying a preferred form of the invention;

Fig. 2 is a plan view of the lower portion of the 55 head of the machine; and

Fig. 3 is a view in cross section taken along the line III—III of Fig. 1.

The illustrated embodiment of the invention is 60 shown as applied to a fastening inserting machine of the type disclosed in United States Letters Patent No. 1,106,393, granted August 11, 1914 on an application filed in the name of Fred. L. MacKenzie. The illustrated machine is provided 65 with a raceway (not shown) for delivering tacks or other fastenings to a nozzle 10 having a passage through which fastenings are driven into the work. A driver 12 is secured to the lower end of 70 a driver bar 14 reciprocating in ways formed in the head 16 of the machine which is secured to the 75 top of a vertical column 18.

The machine is provided with a rotating rubber 80 roll 20 which operates to move a work piece toward the nozzle 10 to support and position the work relatively to the nozzle 10 and the driver 12 85 as will hereinafter be described. The roll 20 is provided with a shallow groove 22 which is shaped to fit the heel end of a lasted shoe 24. The groove 22 is so located relatively to the nozzle 10 that the heel end of a lasted shoe will be centered relatively to the nozzle 10. The roll 20 is secured to a shaft 26 by a set screw 28, the shaft 26 being journaled at each end in suitable bearings 30, 32 90 formed in a forwardly extending bracket 34. The collar 36 is secured to the shaft 26 near one end thereof to maintain the shaft 26 and the roll 20 in position in the bracket 34. A pulley 38 is secured to the shaft 26 adjacent to the collar 36 and is provided with a V-groove to receive a round belt 40. The pulley 38 is driven from any suitable 95

source of power and is arranged to be rotated continuously in the direction indicated by the arrow in Fig. 1. The bracket 34 is mounted in a plate 42 and may be moved forwardly or rearwardly to 5 position the shoe 24 which is in engagement with the roll 20 relatively to the nozzle 10 of the machine. The plate 42 is secured to the under side of the machine head 16 by bolts 44, 46. A T-slot 48 (Fig. 3) is formed in the bottom of the plate 10 42 to form ways to receive the rear portion 50 of the bracket 34, the upper part of which is shaped to fit into the T-slot 48. By the use of this construction the bracket may readily be moved to adjusted position in which it is secured by a screw 15 52. The rear portion 50 of the bracket 34 is provided with a slot 56 arranged to receive the screw 52 which permits the bracket 34 to be moved forwardly or rearwardly relatively to the plate 42.

The last 58 on which the shoe 24 is mounted is 20 provided with a metal heel plate 59 (Fig. 1) which is provided with a hole 61 through which tacks or other fastenings are driven into the last to hold a sole member 60 in position relatively to the lasted shoe 24. Thus, when the sole 60 is to be 25 secured to the bottom of the shoe 24 it is necessary to drive the tack through the outsole 60, the insole 62 and the hole 61 into the body of the last. The shoe 24, therefore, must be so located with respect to the nozzle 10 that the hole in the metal 30 heel plate 59 is directly below the nozzle 10. By adjusting the position of the roll 20 by the use of the mechanism described above a lasted shoe will be properly located and no difficulty will be encountered in securing the sole 60 to the shoe. 35 In operating the machine the operator grasps the lasted shoe 24, places the sole member 60 thereon, and lines up the back seam of the shoe 24 with the groove 22 in the roll 20. Since the roll 20 is continuously rotated, the friction set up 40 between the roll 20 and the shoe 24 will cause the shoe to be moved upwardly against the nozzle 10 with the result that the shoe 24 and the sole 60 will be forced together against the nozzle 10 during the operation of the driver 12.

45 The illustrated machine is provided with an old and well-known clutch tripping mechanism which is connected to the nozzle 10. When the nozzle 10 is engaged by the sole 60, as above described, the nozzle 10 is moved upwardly and, through a 50 pin and slot connection, swings a lever 62 in a counterclockwise direction as viewed in Fig. 1. This movement of the lever 62 pulls a link 64 downwardly which releases or trips the clutch of the machine in the manner disclosed in the 55 above-mentioned Letters Patents.

Having thus described my invention, what I claim as new and desire to secure by Letters Patent of the United States is:

1. In a fastening inserting machine, a nozzle, a 60 driver for inserting fastenings into a work piece, and a power-driven rotatable member arranged to engage the work to locate the work relatively to the driver and to force the work against the nozzle during the fastening inserting operation.
- 65 2. In a fastening inserting machine, a nozzle having a passage through which fastenings are driven into a work piece, a driver for inserting the fastenings, and a power-driven roll arranged to engage the work to move the work into fastening 70 receiving position and to force the work against

the nozzle during the fastening inserting operation.

3. In a fastening inserting machine, a nozzle, a driver for inserting fastenings into a work piece, a rotating roll of somewhat yielding material having a groove arranged to engage the work to position the work relatively to the driver and to force the work against the nozzle during the fastening inserting operation. 5

4. In a fastening inserting machine, a nozzle 10 having a passage through which fastenings are driven into a work piece, a driver for inserting the fastenings into the work, and a rotating roll having a groove arranged to receive the work and to position the work relatively to the driver, said 15 roll being arranged also to move the work into fastening receiving position and to force the work against the nozzle during the fastening inserting operation.

5. In a fastening inserting machine, a nozzle 20 having a passage through which fastenings are driven into a work piece, a driver for inserting the fastenings into the work, and a rotating roll of somewhat yielding material provided with a groove, the walls of said groove being arranged 25 frictionally to engage the work to position the work relatively to the driver and to force the work against the nozzle during the fastening inserting operation.

6. In a fastening inserting machine, a nozzle 30 having a passage through which fastenings are driven into a work piece, a driver for inserting the fastenings into the work, and a rotating rubber roll having a groove arranged to receive the work, the walls of said groove being arranged 35 frictionally to engage the work to move the work into fastening receiving position, to position the work relatively to the driver and to force the work against the nozzle during the fastening inserting operation. 40

7. In a fastening inserting machine, a machine frame, means for inserting fastenings in a work piece, a nozzle having a passage through which fastenings are driven into the work piece, a bracket secured to the machine frame, a rotating roll mounted in the forward end of said bracket, said roll having a groove arranged to engage the heel end of a lasted shoe to locate the shoe properly relatively to the nozzle and to force the shoe against the nozzle, and means permitting adjustment of the position of the bracket to locate the groove in said roll relatively to the nozzle to permit a fastening to be driven substantially into the central portion of the heel end of the shoe. 45 50

8. In a fastening inserting machine, a machine frame, means for inserting fastenings in a work piece, a nozzle having a passage through which fastenings are driven into a work piece, a bracket secured to the machine frame, a rotating roll mounted in the forward end of said bracket, said roll having a groove the walls of which engage the heel end of a lasted shoe to locate the heel end of the shoe longitudinally relatively to the nozzle and to force the shoe against the nozzle, and means for securing the bracket in adjusted position to locate the groove in said roll behind the nozzle to insure that a fastening will be driven substantially into the central portion of the heel end of a shoe engaged by said roll. 55 60 65
